UNITED STATES PATENT OFFICE

135,824

DESIGN FOR A FINGER RING

William Segman, Flushing, N. Y.

Application July 22, 1942, Serial No. 107,647

Term of patent 3½ years

To all whom it may concern:

Be it known that I, William Segman, a citizen of the United States, residing at Flushing, in the county of Queens, city, and State of New York, have invented a new, original, and ornamental Design for Finger Rings, of which the following is a specification, reference being had to the accompanying drawing, forming a part thereof.

In the accompanying drawing

Fig. 1 is a top plan view of a finger ring showing my new design.

Fig. 2 is a front elevation thereof.

Fig. 3 is a right elevation thereof.

The essential and characteristic feature of my design resides in the illustrated configuration of the rounded-rib-like ornamentation appearing at the opposite sides of both ends of the shank of the ring, in association with the oval face panel framed therebetween.

I claim:

The ornamental design for a finger ring, as shown and described.

WILLIAM SEGMAN.
